UNITED STATES PATENT OFFICE

2,599,857

METHOD OF MANUFACTURE OF INSULATION FOR COAXIAL CABLES

Raymond Charles Mildner, Oxhey, England, assignor to Telegraph Construction and Maintenance Company Limited, London, England, a company of Great Britain

Application January 13, 1947, Serial No. 721,843
In Great Britain January 18, 1946

4 Claims. (Cl. 18—47.5)

1

This invention relates to improvements in air space electric cables.

In the design of an air space electric cable for the transmission of high-frequency power, it is desirable that the effective permittivity of the cable insulant should be made as low as possible in order to achieve a high efficiency of transmission. In practice this means that as little solid insulation material as possible should be used, particularly at the parts which are subjected to the highest electrical stresses, that is, near the inner conductor or conductors. It is also important that the insulation should be uniform throughout the length of the cable, so as to reduce the electrical reflections from points of discontinuity to a minimum. Such discontinuities might be caused by a change in the effective permittivity of the insulation at points along the cable length, or by changes in the relative dimensions of the inner and outer conductors.

A further principle of design lies in the requirement that the inner conductor or conductors should be mechanically coupled, both closely and uniformly along the length, to the outer conductor, so as to minimise relative movement of the conductors by reason of handling or differential thermal expansion. In practice these various requirements are conflicting, and practical designs attempt to achieve a compromise.

One known method of constructing a cable, which partly achieves the desirable characteristics noted above, is as follows: The inner conductor is lapped with a circular thread of insulating material of about 1 mm. diameter and a pitch of about 2 cm. This assembly is then provided with an extruded outer sleeve of flexible plastic material, which serves the purposes of locking the thread assembly, giving the cable construction a measure of robustness and providing a watertight covering.

The limitations of this design are due to the maximum size of thread which can be used, the need for avoiding an exceptionally long lay to the thread and the impossibility of locking the thread securely to the inner conductor, because the inner conductor tends to be distorted by the lateral pressure of the thread. In practice, an effective permittivity of about 1.4 with insulating material of permittivity 2.3 is as low as can be achieved.

It has been realised that the use of thread of rectangular cross-section, in which one narrow side is laid along the inner conductor of the cable and the wide sides lie radially, would provide a more advantageous construction than that which incorporates a circular thread.

2

It has been proposed, for instance, that such helical threads should be formed by extrusion around a central conductor by means of a rotating die. In practice, however, it is extremely difficult to form such a thread with the required shape and uniformity owing to the sensitivity of the process to minor fluctuations in the pressure and temperature, which may occur within the extrusion machine.

10 It has also been proposed, in a transmission system having concentric conductors in which the outer conductor is supported by a spiral strip of insulation material with its inner edge coiled around the inner conductor, to form the helical strip by shaving a so-called "spiral" ribbon from the edge of a hollow cylindrical mass of hard rubber of such dimensions that, when stretched out, the ribbon will assume the desired helical shape. In practice it is difficult to form a hollow 15 cylindrical mass of insulating material in the requisite lengths with a uniformity of inner and outer diameters sufficiently great for a satisfactory construction.

20 The present invention has for its object a method of producing, in helical form, a membrane-like thread which can be used in the construction of an air space cable having greatly improved characteristics, both electrical and mechanical, over other constructions hitherto proposed. Furthermore there are no practical limitations to the length of cable which can be produced in this way.

25 According to the present invention helical strip insulation material for use in the manufacture of an electric cable of the air space type is obtained by the application to a former of predetermined size of a layer of dielectric material, cutting the layer into a short pitch helix, and then separating the helix so formed.

30 35 40 In carrying out the invention a former or support which is of the same or substantially the same diameter as the central conductor or coil of the cable to be constructed has applied, such as by extrusion, a layer of dielectric material, and 45 from this layer is obtained by cutting a short pitch helix, which, after removal from the former and the necessary expansion, is preferably subjected to heat treatment to remove any stress set up by the expansion from a short pitch to an open pitch helix.

45 50 With this method it is possible accurately to control the dimension of the resultant helix since the former prevents any deformation of the insulation layer during the cutting operation and the dimensions of both the inner and outer diam-

eter of the strip can be uniformly varied throughout the length of the helix to suit the design of cable for which it is required.

As applied to a cable having coaxial conductors, the helical membrane may be directly mounted on the inner conductor or applied over a layer of insulation previously applied to the conductor.

For a large size cable, two helical membranes may be used, the innermost membrane being locked in position on the central conductor by an extruded layer of insulation and over which the outer membrane is applied.

The outer conductor is applied direct to the dielectric membrane or over an extruded sleeve of insulation. In the case of a cable having twin or multiple conductors, the helical membrane is used to locate the conductors and for this purpose is preferably provided with edge slots to accommodate each conductor, the latter being locked in their relative positions by securing means, which may conveniently consist of a second helical membrane.

The invention is illustrated in the accompanying drawings in which Figure 1 is an elevation showing the former or support with a layer of dielectric and the method of cutting a helical membrane thereon.

Figure 2 is an elevation showing a short length of helical membrane after removal of the support and after it has been extended to increase the pitch and as in the final cable assembly.

Figures 3, 4 and 5 are end views of the helical membrane with different forms of locating slots for use in the manufacture of a multiconductor cable.

Figures 6, 7 and 8 are longitudinal sectional views of three different types of coaxial cable constructions built up with the membrane or membranes of this invention, Figures 6a, 7a, 8a being end views thereof.

Figures 9, 10 and 11 are views in elevation illustrating the application of the helical membrane to multiconductor cables, Figures 9a, 10a, and 11a being end views thereof.

Figure 12 is a part sectional elevation illustrating a device for relieving the stress in an extended helical membrane.

Referring more particularly to Figure 1 a layer of insulation 1 is applied by extrusion or other known means to a central support 2, which may consist of wire or rod. The size of the support will of course be varied to suit requirements but it is substantially of the same diameter as the central conductor or core to which the helical membrane is subsequently to be applied. The insulation may consist of polythene, polytetrafluoroethylene, polystyrene or other suitable dielectric. The insulating cover may be made to conform accurately to the desired dimensions by known methods. Thus the inner diameter as represented by x may be made to conform closely to that of the support by cooling the core so formed slowly as it issues from the extruder, or by the application of external pressure as it cools. The outer diameter as represented by y may be adjusted to any desired accuracy by shaving it with a cutting tool in a subsequent operation. The insulated core is then given a fine helical cut 3 of very short pitch through the insulating layer as far as the support. At the same time it is parted from the support 2 across the narrow section where it may be adhering. The helical thread 4 so formed is now unwound from the support by rotating the free end at a predetermined rate around the latter, in such a manner that it re-

tains its helical form as it becomes separated from the support. This support may now be discarded, when the helical thread element shown in Figure 2 will be obtained, the pitch being some five to twenty times that of the original cut.

In the construction shown in Figures 6 and 6a the helical membrane supports an intermediate layer of insulation 6 applied by extrusion in the form of a sleeve which acts to lock the inner conductor and its surrounding thread or membrane 4 into fixed relationship with one another. An outer conductor 7 is then applied over the insulation sleeve 6. A protective sheath 8 is applied over the conductor 7 to protect the conductor from corrosion and moisture.

The outer conductor may be of braided conducting wires, metal tape either helically or longitudinally applied, a lead sheath or some other desired form of semi-flexible conducting cylinder.

It will be understood that the cable may be comprised of several layers of helical membrane, separated by extruded longitudinal or lapped coverings in the case where the diameter ratio of outer to inner conductor is very large. The direction of lay may be reversed with successive layers, in which case the separators may be omitted.

Thus as shown in Figures 7, 7a which illustrate a coaxial cable constructed in accordance with the invention, two helices, an inner helix 9 and an outer helix 10, are wrapped around a central conductor 11, being separated by an extruded insulating covering 12, and enclosed by an extruded outer conductor 13 which may be a lead sheath.

Referring now to Figures 8, 8a, there is shown a central conductor 11, provided with a layer of insulation 14, over which the helical membrane 4 is applied, an outer conductor 15, consisting of a layer of tape folded longitudinally, being directly supported by the membrane. 17 is a waterproof covering. This form of the invention is particularly applicable to cable constructions designed to have a low capacitance, necessitating a central conductor of small diameter. By use of an inner insulation layer 14, the inherent weakness of the conductor is overcome and a better locking effect is secured between the membrane and the central core by reason of the increased diameter.

Similarly the helical membrane construction may be used in conjunction with other known forms of cable insulation.

(a) The inner conductor may first be spiralled with a circular thread of suitable insulating material and then the helical membrane may be applied thereon.

(b) The helical membrane may be applied over a braiding of insulating threads which surround the central conductor.

(c) The helical membrane may be applied over or under a disc-spaced construction.

The helical membrane may also be applied to the construction of multi-conductor cables, two or more slots being cut in the periphery of the core illustrated in Figure 1 prior to elongating the membrane. These slots may be cut longitudinally or helically. The conductors are laid in the slots and locked in position by means of an insulating thread or by means of a second helical membrane. The helical membrane supporting the conductors may conveniently be wound on a central insulating rod or tube so as to provide a coherent structure on which to as-

semble the conductors and to define precisely the lay of the helix.

Referring now to Figures 9, 9a the cable is built up on a central tube 19 of insulating material carrying a helical membrane 18 provided with deep slots 20 to locate the conductors 21 which are locked in position by a helically wrapped thread 22.

Referring to the construction illustrated in Figures 10 and 10a the central tube 19 supports a helix 18 which is similarly slotted to receive the conductors 21, the latter being locked in position by a second helix 23 which is of the same external diameter as the slotted helix 18 but whose inner diameter is of a size to hold the conductors in the bottom of the slots.

In the somewhat similar construction illustrated in Figures 11, 11a, a helical membrane 25 having shallow slots 26 is supported by the insulating tube 19. The conductors 21 are locked in position by a second and outer helix 29.

It will be appreciated that while no electromagnetic screen is shown in the several constructions illustrated in Figures 9 to 11, such a screen may be used, in which case it could be supported directly or indirectly by the helical membranes.

The extension of the thread from its position when cut as shown in Figure 1 to its final form in Figure 2 sets up some strain in the plastic material. Provided the ratio of the outer to inner diameter of the thread is low and the ratio of the final pitch of the membrane thread to its thickness is not excessive, this strain can be accommodated by a distortion of the membrane formed by the thread. Where both of these ratios are high, the strain involved may be excessive and it may be necessary to carry out a further forming process. In such a case the thread is extended approximately to its final pitch and is then passed between hot rollers which raise the temperature of the material to its softening point but well below its melting point. The temperature is not critical because in all practical cases the required strain should not exceed about 10 to 15%.

Referring now to Figure 12 there is illustrated a form of heating device through which an expanded helix is passed in order to relieve the stress set up by the expansion operation. The device comprises essentially a revolving tube 31 mounted to rotate in bearings 37 and incorporating a worm and worm wheel drive 38. Located centrally within the tube 31 are revolving conical rollers 35, between which the helical membrane 30 is fed. Rollers 35 are fast on spindles 39 journaled in bearings 36 in the tube, which is formed with an increased wall thickness or shouldered portion 40 for this purpose and to provide a circumferential bearing 41 for a worm annulus 42 meshing with a worm 43. The annulus 42 is formed on its opposite faces with rack teeth 44 which are in driving engagement with bevel pinions 45 on the roller spindles 39. Located on opposite sides of the rollers 35 are slip rings 46, 47 for the introduction through corresponding apertures 48, 49 of hot and cold air respectively for heating and cooling the membrane. In operation the membrane 30 is fed in the direction of the arrows through the tube interior, being guided by a series of rollers 50 located downstream and upstream of the driven rollers 35, rollers 50 being freely mounted on studs 51 and carried by the tube 31.

It will be understood that cables having a wide range of electrical and mechanical characteristics

can be designed by using a membrane construction in accordance with the present invention. In general the effective permittivity can, for a given robustness, be made lower than by the use of conventional constructions. Thus a cable of 0.75" diameter inside the outer conductor formed with a polythene membrane of 15 mils thickness having a pitch of 0.2" has an effective permittivity of approximately 1.10.

What I claim is:

1. A method for the manufacture of insulation material for use in an electric cable including inner and outer conductors and an interposed helix of solid insulation; said method comprising extruding upon a former of predetermined size substantially the same as the size of the inner conductor to which the material is to be applied a layer of dielectric material of sufficient inherent rigidity to provide, when formed as a short pitch helix and subsequently extended, effective mechanical connection of the inner and outer conductors, helically cutting the dielectric material of said layer into a short pitch helix of solid insulation having a prescribed internal dimension corresponding to the external dimension of the inner conductor, and extending said short pitch helix.
2. A method for the manufacture of insulation material for use in an electric cable including inner and outer conductors and an interposed helix of solid insulation; said method comprising extruding upon a former of predetermined size substantially the same as the size of the inner conductor to which the material is to be applied a layer of dielectric material of sufficient inherent rigidity to provide, when formed as a short pitch helix having convolutions of substantially greater radial dimension from inner to outer diameter than axial thickness, effective mechanical connection of the inner and outer conductors, helically cutting the dielectric material of said layer into a short pitch helix having convolutions of substantially greater radial dimension from inner to outer diameter than axial thickness, and separating the helix so formed from the former to provide a continuous helix of solid insulation having a prescribed internal dimension corresponding to the external dimension of the inner conductor.
3. A method for the manufacture of insulation material for use in an electric cable including inner and outer conductors and an interposed helix of solid insulation; said method comprising extruding upon a former of predetermined size substantially the same as the size of the inner conductor to which the material is to be applied a layer of dielectric material of such inherent rigidity that when cut helically into a short pitch helix and separated from the former the helix will have an internal dimension substantially constant throughout the length of the helix so as to enable said helix to provide effective mechanical connection between the inner and outer conductors, and helically cutting the dielectric material of said layer into a short pitch helix.
4. A method for the manufacture of insulation material for use in an electric cable including inner and outer conductors and an interposed helix of solid insulation; said method comprising extruding upon a former of predetermined size substantially the same as the size of the inner conductor to which the material is to be applied a layer of dielectric material of sufficient inherent rigidity to provide, when formed as a helix having 75 convolutions of substantially greater radial di-

mension from inner to outer diameter than axial thickness, effective mechanical connection of the inner and outer conductors; helically cutting the dielectric material of said layer into a short pitch helix having convolutions of substantially greater radial dimension from inner to outer diameter than axial thickness and leaving said helix on and in contact with said former during the cutting of successive convolutions; and separating the helix so formed from the former to provide a continuous helix of solid insulation having a prescribed internal dimension corresponding to the external dimension of the inner conductor.
